UNITED STATES PATENT OFFICE.

RAY P. PERRY, OF UPPER MONTCLAIR, NEW JERSEY, ASSIGNOR TO THE BARRETT COMPANY, A CORPORATION OF NEW JERSEY.

PROCESS OF COKING PITCH.

Application filed April 5, 1922. Serial No. 549,864.

As distinguished from the coking of coal and of certain grades of coal-tar pitch which are not or do not become thoroughly liquid in the coking process, my invention relates to 5 the coking of coal-tar pitch and the like under conditions where or when the material is in such a condition that it is introduced in a liquid condition into the coking chamber or becomes liquefied by heat in such chamber 10 in the course of the coking process or before the coking operation takes place.

In most types of modern equipment for coking coal, such for example as so-called by-product coke ovens or gas retorts, it is 15 customary to supply the heat required for the coking process through the walls of the coking chamber. For example, in a by-product coke oven the heat is supplied through the side walls of the oven, the heating flues in these side walls and the heating 20 gases in the flues being distributed and regulated so as to produce a substantially constant and uniform temperature over the entire side walls of the oven. This permits 25 thorough and substantially uniform coking of the entire charge of coal in the oven, the coking progressing from the two sides toward the median line of the charge.

Because of the successful coking of coal in 30 such by-product ovens, it was expected that coal-tar pitch could be satisfactorily coked in the same ovens and in the same way, but in the attempts to coke liquid or liquefiable coal-tar pitch serious difficulties have been 35 encountered which render the process unsuccessful and make the coke unsatisfactory for certain purposes. The pitch, upon being 40 heated to a certain critical temperature, appears to have some of its constituents 45 composed, or at least there is a very large evolution of gases and vapors resulting in sudden and rapid development of pressure, accompanied by expansion and foaming of the liquid mass. This critical temperature depends upon the melting point and other 50 characteristics of the pitch and can be easily ascertained by trial.

If a mass of liquid or liquefiable pitch is 55 heated in a by-product coke oven in the manner customary in coking coal, there sets up in the pitch, when it is in a liquid condition, a natural thermal circulation or convection currents by which the entire liquid mass is raised to a substantially uniform 60 temperature throughout, and consequently

when a sufficient amount of heat has been supplied to reach the critical temperature mentioned above, it will be noted that the entire mass at one time may be at this temperature as distinguished from the conditions present in coking coal. Coal being non-liquefiable, does not have a thermal circulation and does not reach a uniform temperature throughout, but on the contrary the heat penetrates slowly and the coal is coked slowly and progressively from the two sides towards the center with a consequently less violent or sudden evolution of gases.

I have discovered that the unsatisfactory condition and troubles arising in coking liquid or liquefiable pitch can be minimized or avoided by applying from the top or from the sides near the top sufficient heat for converting the top portion only of the liquid pitch into coke with the accompanying large 70 gas evolution from that portion, while the remainder of the charge of pitch in the oven, although a considerable portion or all of it may be in liquid form, is nevertheless maintained at a temperature below that at which 75 the heavy gas evolution takes place in changing from pitch into coke. After this top portion of the pitch charge has passed the critical gas evolution stage, I continue the 80 coking progressively in a downward direction either continuously or intermittently, applying a sufficient amount of heat for converting only a small portion at a time of the liquid pitch near the top into coke, while 85 the balance of the charge below, although it 90 may be liquid, is maintained at a temperature below the heavy gas evolution stage.

The invention will be understood from the description in connection with the drawings which illustrate an apparatus for carrying out the process. In the drawings

Fig. 1 is a vertical section of an oven.

Fig. 2 is a section along the line *a—a* of Fig. 1.

Fig. 3 is an end section of a modified form 100 of oven.

In the drawings reference character 1 indicates the wall of an oven which is provided with a bottom 2 and a cover 3. An outlet 4 extends through the cover 3, and a 105 pair of openings are shown at 5 through which the material may be charged.

A series of horizontal conduits or flues 6, 7, 8, 9, etc., extend through the walls of the oven. These flues 6, 7, etc. are connected by 110

means of the pipes 6', 7', etc. which are furnished with valves 6'', 7'', etc. with a feed or inlet pipe 10 for hot gases or for hot products of combustion, and the other end of these conduits or flues are connected to a common header 11, through which the hot products are discharged.

In the modification shown in Fig. 3 the apparatus is substantially the same as above described except that the oven 1' is made with walls which flare outwardly in an upward direction, and this oven is provided with an inlet pipe 5' near the bottom thereof while the top or cover 3' is made removable.

The operation is as follows:

The liquid or liquefiable coal-tar pitch is introduced through the inlet openings 5 either in the solid or liquid state. Assuming that the oven is in a hot condition from a preceding coking operation, the pitch will be melted if the same is not already in a molten condition. Heat will be supplied to the oven through the upper flues 6 by opening the valve 6'' while the remaining part of the oven is not subjected to the increased heat. As a result of this method of heating, the pitch forming the upper layer or upper portion of the mass will be heated to the critical temperature with a consequent evolution of gas and resulting coking of this portion. After the upper portion of the charge of pitch has been coked, heat may be applied in a lower set of flues 7 to cause the coking of the next layer of pitch to take place in a similar way. By then applying heat in the lower flues, the coking will progress downwardly toward the bottom.

It is possible to perform the coking operation as above described in such a manner that the pitch at distances considerably below the portion that is being coked will not be liquefied. In this way the convection currents or circulation of pitch may be minimized, thereby further limiting the danger of sudden evolution of gas from an exceedingly large mass of the pitch.

When the coking is produced in the oven, as indicated in Fig. 3, the molten pitch is supplied through the inlet 5' and as the coking takes place near the top, the layer of coke formed may be removed, thus permitting the introduction of more pitch through the inlet 5' and raising the level of the mass so that another layer at the top may be coked without at any time fully discharging the oven.

The coke made in accordance with this process is substantially free from sulfur and ash and possesses very high mechanical strength so that the same can be used in a foundry cupola. The coking of the pitch from the top downwardly appears to make the same very much stronger than the ordinary methods of coking. It will be clear

that this method of coking pitch may be carried out in a vertical gas retort or other coking chamber such as the ordinary type of beehive oven, the important and distinguishing feature being that the heat which is to cause the coking of the pitch should be supplied first at or near the top of the pitch under such conditions that there would be no objectionable thermal circulation or convection currents throughout the mass. Care should be exercised regardless of the sort of oven in which the coking is made to take place, so that the heat would not be supplied in sufficient quantities throughout the entire mass to bring the mass to the temperature at which there would be a large gas evolution stage at one time. The thermal circulation incidental to the liquid condition of the pitch seems to be of no particular disadvantage if the pitch is maintained below the large gas evolution coking stage. An advantage that is obtained by coking the pitch downwardly in a by-product coke oven, for example, is that the evolved gases can be collected and the valuable by-products therein recovered.

I claim:—

1. The process of coking a mass of liquid hydrocarbon pitch, which consists in externally supplying sufficient heat to the upper portion of the pitch to convert said upper portion into coke, then externally supplying sufficient heat to the next lower portion of pitch to convert same into coke, and progressively coking the balance of the charge of pitch in a downward direction.

2. The process of coking a mass of hydrocarbon pitch which is liquid or liquefiable by heat, which comprises supplying the heat for coking first to the upper portion of the mass and then progressively downward through the mass, while retaining the mass wedge shaped with the narrower portion downwards.

3. The process of coking hydrocarbon pitch that is solid at normal temperatures, which comprises coking an upper portion of the mass while maintaining a lower portion of the mass in a liquid but non-coking condition, any lower layer of said mass being narrower than a layer thereabove.

4. The process of coking a mass of liquid hydrocarbon pitch, which comprises coking an upper portion of the mass while maintaining a lower portion of the mass in a liquid but non-coking condition, and adding more pitch to the liquid non-coking portion.

5. The process of coking a mass of liquid hydrocarbon pitch, which comprises coking an upper portion of the mass while maintaining a lower portion of the mass in a liquid but non-coking condition, removing the coked portion and adding more pitch to the liquid non-coking portion.

6. The process of coking liquid hydro-

carbon pitch in an oven, which consists in coking first the upper portion of the mass of pitch and then coking the balance of the mass progressively in a downward direction 5 by successively transmitting heat through the walls of the oven to lower planes of the mass.

7. The process which comprises applying heat to the upper portion of a mass of hydro- 10 carbon pitch, until coking of said portion takes place, and then applying heat to a lower portion of the pitch, said heat being transmitted to both said portions through the walls of the container in which the pitch 15 is being coked.

8. The process of coking a liquid hydro- carbon pitch in an oven, which consists in coking an upper portion of the mass by 20 means of heat transmitted through the walls of the oven without coking any portion therebelow until the coking of such upper portion is substantially complete.

9. The process of coking in an oven a mass of hydrocarbon pitch which is liquid or liquefiable by heat, which comprises supplying the heat for coking first to the upper portion of the mass and then progressively downward through the mass, and recovering the volatile constituents driven off from the hydrocarbon pitch. 25

10. The process of coking in an oven a mass of hydrocarbon pitch which is liquid or liquefiable by heat, which comprises transmitting the heat for coking through the walls of the oven first to the upper portion 30 of the mass and then progressively downward through the mass, maintaining in the oven an atmosphere which will not support combustion, and recovering the volatile constituents driven off from the hydrocarbon 35 pitch. 40

In testimony whereof I affix my signature.

RAY P. PERRY.
